UNITED STATES PATENT OFFICE.

THOMAS EDGAR ADAMS, OF CLEVELAND, OHIO.

DESIGN FOR AN ELECTRIC-ARC-LAMP BODY.

SPECIFICATION forming part of Design No. 25,099, dated January 28, 1896

Application filed September 21, 1895. Serial No. 563,259. Term of patent 14 years.

To all whom it may concern:

Be it known that I, THOMAS E. ADAMS, a citizen of the United States, residing at Cleveland, in the county of Cuyahoga and State of Ohio, have invented and produced a new and original Design for Electric-Arc-Lamp Bodies, of which the following is a specification, reference being had to the accompanying drawings, showing a part thereof.

My invention relates to a new and original design for electric-arc-lamp bodies.

In the accompanying drawings, Figure 1 is an elevation of an electric-arc lamp, showing my new design. Fig. 2 is a sectional view.

The leading features of my design consist in a casing having a curved exterior and made flaring at its lower end with perpendicular flutings and a waving lower-edge line, a cap over said casing with its largest diameter greater than the smallest diameter of said casing, a spherical base, a pear-shaped globe between said casing and base, and raised decorations on said casing and base.

A represents a casing having a flaring lower end B and holes B' at its top. At the top of 25 the casing A a cap C is located and made with a curved top, the largest diameter of said cap being of greater diameter than the smallest diameter of the casing. An opening in top of cap is covered by smaller cap 30 C'. The casing is made with raised decorations *a*, which are burnished.

D represents a base, the general form of which is approximately spherical, with a ring b at its top. The base (and ring which forms 35 a part thereof), has raised burnished decorations *c*. Between the casing A and base D a pear-shaped globe E is located.

What I claim is—

The design for an electric-arc-lamp body 40 herein shown and described.

THOMAS EDGAR ADAMS.
